[57] CLAIM

The ornamental design for a central control unit for personal computer, as shown and described.

DESCRIPTION

FIG. 1 is a front top and right side perspective view of a central control unit for personal computer showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof;

FIG. 8 is a sectional view thereof taken along line VIII—VIII of FIG. 2;

FIG. 9 is a sectional view thereof taken along IX—IX of FIG. 2; and,

FIG. 10 is a perspective view thereof showing the control unit in an operative state with a monitor, keyboard, mouse and disc being shown in broken lines for illustrative purposes only and form no part of the claimed design.

FIGS. 1 and 10 are shown on slightly reduced scale.
